No. 846,395.

PATENTED MAR. 5, 1907.

J. J. BUSENBENZ.

GAS MANUFACTURING APPARATUS.

APPLICATION FILED MAY 26, 1906.

UNITED STATES PATENT OFFICE.

JACOB J. BUSENBERG, OF CHICAGO, ILLINOIS, ASSIGNOR TO INDUSTRIAL GAS CONSTRUCTION CO., OF CHICAGO, ILLINOIS, A CORPORATION OF ILLINOIS.

GAS-MANUFACTURING APPARATUS.

No. 846,395.

Specification of Letters Patent.

Patented March 5, 1907.

Application filed May 26, 1906. Serial No. 318,826.

To all whom it may concern:

Be it known that I, JACOB J. BUSENBERG, a citizen of the United States, residing at Chicago, in the county of Cook and State of Illinois, have invented a new and useful Gas-Manufacturing Apparatus, of which the following is a specification.

My invention relates particularly to means for injecting air and volatile liquid fuel, such as gasoline or alcohol, in atomizing relationship into the mixer-chamber of gas-manufacturing apparatus.

My primary object is to provide an injecting device adapted for use in apparatus for the manufacture of fixed gas from the volatile liquid fuels, such as the hydrocarbon oils and alcohol, without the employment of heat in the manufacturing process.

The invention is illustrated in its preferred embodiment in the accompanying drawing, which shows a sectional view of the device.

In the drawing, A represents a fragment of one wall of a mixer-chamber, and A' my improved atomizing and injecting device applied thereto. The device A' comprises a casing a, connected by cap-screws a' with the chamber A; an injector-tube a², having its inner end extending through a central opening in the inner end wall a³ of the casing and held by nuts a⁴, screwed onto the tube and clamping said wall between them; a gate-valve a⁵, controlling the injector-tube and having a stem a⁶ projecting through a lateral wall of the casing a; a nozzle a⁷, connected with the outer end of the casing a and having its point entering the injector-tube a², and an air-conduit a⁸, connected with the upper side of the casing and having communication with the external atmosphere.

The wall of the mixer-chamber A, with which the casing a is connected, is provided with a relatively large opening a⁹, which is covered by the inner end of the casing. The casing is flanged externally at its inner end to receive the cap-screws a'. The threaded inner end of the injector-tube a² passes freely through an opening a¹⁰ with which the wall a³ of the casing is provided. The casing of the valve a⁵ has a lateral extension a¹¹, which is received by a stuffing-box a¹², provided with a flange a¹³ and connected with the casing-wall by cap-screws a¹⁴. The body of the stuffing-box passes freely through an opening a¹⁵ in the wall of the casing. The details of

the valve a⁵ need not be explained, as the valve is of common construction. The nozzle a⁷ comprises a tubular member a¹⁶, having its inner end projecting through an opening in the outer end of the casing a, the member a¹⁶ being provided with an external flange 60 a¹⁷, which is connected by cap-screws a¹⁸ with the end of the casing; a tubular member a¹⁹, extending within the member a¹⁶ and having threaded connection a²⁰ with said member; an annular nut a²¹, encircling the shank of 65 the member a¹⁹ and having its inner end provided with internal threads engaging with external threads on the outer ends of the member a¹⁶; a gasket a²², confined between an internal shoulder of the member a²¹ and 70 the outer end of the member a¹⁶; a packing-ring a²³, having screw connection with the member a²¹; a tubular member a²⁴, having screw connection with the member a²³; a gasket a²⁵, interposed between the member 75 a²⁴ and the member a²³; a tubular member a²⁶, having screw connection a²⁷ with the member a²⁴; a pipe a²⁸, having screw connection with the member a²⁶, and a pipe a²⁹, having screw connection with a lateral opening in 80 the member a¹⁶ and communicating with an annular chamber a³⁰ between the member a¹⁹ and the member a¹⁶.

The inner end of the tubular member a¹⁶ projects slightly into the outer end of the injector-tube a², and the tube a² is provided near its outer end with a set of openings a³¹, and at a greater distance from its outer end with a set of openings a³². The injector-tube a² has a bore which tapers from its outer end 85 to a point just in the rear of the opening a³² as indicated at a³³, and said bore then expands, as indicated at a³⁴, to a point just inside of the opening a³². The annular passage a³⁰ between the internal surface of the member a¹⁶ and the external surface of the member a¹⁹ converges at the point of the nozzle, as indicated at a³⁵. The member a¹⁹ has a tapering point a³⁶, which projects into the tapering bore at the inner end of the member a¹⁶. The member a²⁶ has a bore which is of successively-reduced diameters as the point of the member is approached, where a minute orifice a³⁷ is provided. The point of the member a²⁶ projects slightly beyond the 90 point of the member a¹⁶. The member a¹⁹ is adjustable with relation to the member a¹⁶ to 95 vary the tapering annular orifice at a³⁵, and

the member a^{26} is adjustable with relation to the member a^{19} to still further vary the orifice.

5 The conduit a^8 is provided at its lower end with an external flange which is connected with the top of the casing a by cap-screws a^{38} . The casing is provided with a drain-pipe a^{39} .

10 In the operation of the device oil under pressure is introduced through the pipe a^{28} and internal nozzle a^{26} , and air under pressure is introduced through the pipe a^{29} and the annular passage a^{30} , the streams meeting at the tip of the nozzle in such relation as to thoroughly vaporize or atomize the oil. The 15 jet issuing from the nozzle into the injector-tube a^2 draws in air from the external atmosphere through the passages a^{31} , and the augmented stream draws in additional air 20 through the passages a^{32} , the mixed air and vapor in proportions suitable to form a fixed gas then passing through the injector-tube into the mixer-chamber, it being assumed that the valve a^5 is open. In practice the 25 mixer-chamber is connected with a gasometer which controls valves regulating the passage of oil and air through the pipes a^{28} and a^{29} and the intake of air through the conduit a^8 . The device renders practicable the manufacture 30 of gas from a volatile hydrocarbon oil or from alcohol without the employment of heat. In practice I subject the oil passing through the pipe a^{28} and the air passing through the pipe a^{29} to a common pressure 35 controlled by a pressure-reducing valve, the source of compressed air being a tank containing air under high pressure.

It will be noted that the intermediate tubular member a^{19} has a straight reduced bore 40 at its point, and the interior tubular member a^{26} has a non-tapering point portion entered in said bore; also, the outer end of the member a^{19} projects beyond the nut a^{23} , so as to facilitate adjustment when the nut a^{24} is disconnected and the internal nozzle member 45 a^{26} is withdrawn. From this description it will be at once understood that the size of the annular passage at a^{35} may be readily regulated.

50 I have described my invention in detail for clearness of understanding only.

What I regard as new, and desire to secure by Letters Patent, is—

1. The combination of a casing having 55 aligned openings at opposite ends, an injector-tube extending through the opening at the inner end of said casing and equipped with nuts clampingly engaging the inner end wall of the casing, a valve connected with said injector-tube, and extending through a lateral wall of said casing, and a nozzle connected 60 with the outer end of the casing and communicating with the outer end of said injector-tube, said nozzle having a liquid-passage and 65 an air-passage for the purpose set forth.

2. A device of the character set forth, comprising a casing, an injector-tube therein, and a nozzle comprising a tubular member extending through a wall of said casing, and having an orifice presented to the injector-tube, said nozzle comprising an outer tubular member provided with an external flange secured to the casing-wall, an internal tubular member forming an annular passage with the outer member, a pipe connected with said annular passage, and a pipe connected with the interior of the internal member. 70

3. A device of the character set forth, comprising a casing, an air-conduit connected therewith, an injector-tube within the casing 80 equipped with a valve having a stem extending through a lateral wall of the casing, and a nozzle comprising a tubular member extending through the outer end of the casing, a laterally-extending pipe connected with said member, a tubular member having threaded connection with said first-named tubular member and having a tapering point entered in a tapering bore at the point of said first-named tubular member, an internal tubular 85 member extending through said second-named tubular member, and a pipe in communication with the interior of said third-named member.

4. A device of the character set forth, comprising a casing, an injector-tube within said casing, and a nozzle applied to an end of said casing and communicating with said injector-tube, said nozzle comprising an outer tubular member, an intermediate member extending through the outer tubular member and having screw connection therewith, a packing-gland connected with said first-named tubular member and through which the shank of the second-named tubular member 95 extends, and an internal tubular member extending through the second-named tubular member and adjustably connected with said packing-gland. 100

5. A device of the class set forth comprising a casing, an injector-tube within the casing, a valve controlling said injector-tube and having a stem projecting through a lateral wall of said casing, and a nozzle applied to an end of said casing, said nozzle comprising an outer tubular member, a pipe extending laterally therefrom and in communication with the interior of said tubular member, an intermediate tubular member extending substantially through the outer tubular 110 member, and forming therewith an annular passage, screw connections between said tubular members, a packing-gland encircling the shank of the second-named tubular member, and adjustably connected with the shank 115 of the first-named tubular member, and an internal tubular member extending through the second-named tubular member and adjustably connected with said packing-gland. 120

6. The combination with a mixer-chamber 130

wall having an opening, of a casing having its end secured to said wall and covering said opening, an injector-tube extending through the inner wall of said casing, a valve connected with said injector-tube, a packing-gland connected with a lateral wall of said casing and receiving said valve and a nozzle extending through the outer end wall of said casing and in communication with said injector-tube.

7. The combination of a casing, an injector-tube therein, and a nozzle comprising an external tubular member having a bore with a tapering orifice in communication with the injector-tube, an intermediate tubular member with a tapering point entered in said orifice, said second-named tubular member being adjustably connected with said first-named tubular member, and an internal tubular member extending through said second-named tubular member and into the orifice of the first-named tubular member, said third-named tubular member being adjustable with relation to said first and second named tubular members.

8. The combination of a casing, an injector-tube therein having its outer end extend-

ing to near the outer end of the casing, said injector-tube having a bore tapering inwardly from its outer end and then expanding, and having two sets of openings communicating with said bore at the tapering portions thereof, and a nozzle connected with the outer end of the casing and having liquid and air passages communicating with said injector-tube adjacent to the openings therein.

9. The combination with a mixer-chamber wall having an opening, of a casing having one end secured to said wall and covering said opening, an injector-tube extending through the inner end wall of said casing, a valve connected with said injector-tube and having an operating-stem extending through a lateral wall of said casing, an atmospheric-air-intake conduit connected with said casing, and a nozzle extending through the outer end wall of said casing and provided with a liquid-passage and an air-passage for fluids under pressure.
